INTERIOR WALL CONSTRUCTION FOR
BUILDINGSDavid E. Ross and Louis M. Alt, La Fayette, Ind.,
assignors to Rostone, Incorporated, La Fayette,
Ind., a corporation of Indiana

Application January 13, 1934, Serial No. 706,548

17 Claims. (Cl. 189—1)

This invention is an improvement in fabricated buildings of the type shown in the companion application of David E. Ross filed December 7, 1933, Serial No. 701,380, which matured in Patent #2,027,882 on Jan. 14, 1936, and provides novel means for and method of attaching fabricated interior walls or wall covering to the steel framing of such buildings. The invention however is applicable to other types of buildings where it is desired to cover the interiors with fabricated material in a quick and efficient durable manner.

The material used for the interior walls or finish thereof may be compo-board, plaster board, or other material suitable for the purpose, and we will hereinafter refer to it as wall board meaning thereby to include any material suitable or usable for such purposes. The wall board is pre-fabricated into sheets or blocks of suitable dimensions, according to the surface area to be covered thereby, and such wall board is provided with novel attaching members adapted to engage novel supporting members attached to the interior of the framing, the construction being such that the wall board can be easily placed and secured in position, as hereinafter explained.

The accompanying drawings illustrate one practical embodiment of the invention, and we will describe the same with reference to said drawings, and thereafter set forth in the claims the essentials of the invention and novel features of construction and combinations of parts for which protection is desired.

In said drawings:—

Fig. 1 is a fragmentary interior view of part of a building showing various features of the invention.

Fig. 2 is an enlarged detail vertical section of the lower end of one of the uprights on line 2—2, Fig. 1.

Fig. 3 is an enlarged vertical sectional view through the inner part of the wall showing the connecting devices in elevation and in section.

Fig. 4 is a face view of one of the supporting clips.

Fig. 5 is a side view of such clip and Fig. 6 is an end view thereof.

Fig. 7 is a detail view showing the clip with expanding pin, in position for attachment to the wall board in full lines and showing in dotted lines the clip driven into the board. Fig. 8 is a similar sectional view showing the clip driven home after the expanding pin is removed.

Fig. 9 shows a clip attached to the wall board by screws.

Fig. 10 is a detail view showing the wall corner finish.

Fig. 11 is a sectional view on line 11—11, 5 Fig. 10.

Fig. 12 is a sectional view on line 12—12, Fig. 10.

Fig. 13 is a detail view of the corner finish.

Fig. 14 is a perspective sectional view of the corner finishing bracket on line 14—14, Fig. 11.

Fig. 15 is a horizontal section of the corner connections disconnected.

Fig. 16 is a sectional view of a form of the connecting devices.

The framing of the building is preferably constructed as described in the aforesaid Ross application, and in brief comprises vertical studs (composed of channel irons, 1, 1, and bracing 1a), spaced apart and bolted to lower and upper channel irons 12, 12a. Attached to the exterior sides of the studs are parallel rows of supporting members 2, upon which the exterior wall blocks B are mounted as explained in said Ross application. While our invention is especially designed for use with such framing, it is not limited thereto.

In applying our invention to buildings, we attach to the interior of the framing rows of wall board supporting members 9, arranged in horizontal parallel series and suitably spaced apart. These members may be applied both to the side walls and to the ceiling of the building as indicated in Fig. 1.

The members 9 are preferably fastened to the studs 1 by the connections 7, 8 as shown in Fig. 3 and described in Ross application Serial No. 675,485, filed June 12, 1933, which matured in Patent #1,986,980 on Jan. 8, 1935. The members may be either fastened direct to the studs 1, as shown in Figs. 2 and 3, or may be spaced out from the channels a distance equal to the thickness of an insulating sheet 11a by means of washers 4, as shown in Fig. 16.

The members 9 are made of resilient metal strips. Each member has a base portion 9a (engaged by the fastening bolt 7, Fig. 3) and upper and lower flanges 9b which are inwardly inclined toward each other; and the extremities of the flanges are preferably formed with half-round beads as at 9c. The flanges 9b are adapted to clamp fasteners 10 attached to the wall board 11 and by which the wall board is supported on the members.

The interior wall board 11 is cut to size and 55

provided with fasteners 10 which are accurately spaced to accord with the spacing of adjacent parallel members 9.

- The fasteners 10 (see Figs. 4-9) are preferably formed of resilient sheet metal. Each fastener has a central transverse portion 10a forming a head approximately quadrangular in section and of a maximum diameter greater than the space between the beads 9b of members 9. It also has 10 outwardly extending portions 10b at opposite sides of the head (see Fig. 6) the outer ends 10c of which are bent downwardly at substantially right angles, and are pronged or toothed as indicated in Fig. 5, so that they can be forced 15 into the wall board. At the junction of parts 10a and 10b are recesses 10d which are adapted to engage the beads of the members 9 when the fastener is engaged therewith, as shown in Figs. 2 and 3.
- 20 Before pressing the prongs of the fastener into the wall board, an expanding pin P (Fig. 7) is driven into the square shaped head 10a of the normal fastener shown in Fig. 6 and in dotted lines in Fig. 7, to expand the normal distance 25 between the opposite prongs as shown in full lines in Fig. 7, and when thus expanded the opposite prongs are approximately parallel. The fastener prongs are then pressed into the sheet of wall board by means of a plunger A (which is part of 30 the equipment preferably used in attaching the fasteners to the wall board) and while the plunger is held depressed the expanding pin P is removed. When the pin P is removed the fastener tends to resume its contracted original 35 shape (see dotted lines Fig. 7) and grips the wall board between the prongs with a vise-like grip. In some cases fasteners without prongs could be used and secured to the wall board by screws, as indicated in Fig. 9.
- 40 Two or more aligned fasteners should be attached to the wall board to engage each supporting member 9 throughout the length of the wall board. To secure the wall board to the members 9 the heads 10a of one row of fasteners are 45 forced between the beads of the related member 9, so that the beads engage the shoulders 10d of the fasteners as shown in Figs. 2 and 3. After one row of fasteners has been engaged with a member 9 the other rows of fasteners can be engaged with the related members 9 throughout the 50 height of the wall board. The wall board thus mounted on the members 9 can be slipped horizontally along the members to closely abut a previously applied adjacent wall board.
- 55 The vertical joints between two adjacent wall boards may be sealed by means of an H-strip 21 as shown in Fig. 1. The exposed portion of this strip 21 may be finished in any color to suit the interior.
- 60 A further advantage of this assembly is the fact that the fasteners and members will not synchronize with sound vibrations; therefore this interior assembly will lessen the transmittal of sound through the walls.
- 65 Members 9 may also be fastened to the ceiling beams 25 to support ceiling wall board 11a, which is provided with fasteners 10 in the same manner as the vertical wall board 11.
- At the corners the joints between the ceiling 70 and sides may be sealed by means of pre-fabricated molding 15, of suitable material (see Fig. 1). Strips 16 preferably of metal (Figs. 10-14) are placed behind the adjacent edges of the wall boards at the corners and may be held in place by 75 means of clips 17 and eye bolts 19, (Fig. 15) un-

til the molding 15 has been slipped into place. The molding is provided with bayonet hooks 18 spaced along the molding in accordance with the spacing of eye bolts 19 on strips 16. The molding 15 is placed between the adjacent edges of the ceiling and side wall boards, at the angles, and the hooks 18 can be engaged with the eye bolts 19 by moving the molding longitudinally, the length of the pieces of molding 15 permitting such movement.

10 The vertical joints between the side walls are similarly covered by molding 15a attached in the same manner as the ceiling molding 15. In the ceiling corners plates 23 (Fig. 1) are secured to cover the joints at the junction of the molding 15 strips (15, 15, 15a).

At the base of the wall board along the floor, a metal base 13, (Figs. 1 and 2) may be used. This base 13 is fabricated of any suitable design in cross-section and may be attached to the adjacent members 9, by means of fasteners 10x similar to fasteners 10 but having their sides extended sufficiently, as shown in Fig. 2, to enable them to be attached to the base and extend through the adjacent wall board 11 and engage the members 9. At the points where the fasteners 10x are located (see Figs. 1 and 2) the wall board 11 is cut away or slotted as at 11c to allow the fasteners to project therethrough. The ends of adjacent base boards, at the corners, are 30 covered by stampings 22, Fig. 1, which also form a neat joint with the vertical molding 15a.

Our interior wall construction is applicable to either metal or wood buildings. The size of the room or area of the wall to be covered and the kind of wall board to be used being selected; the requisite quantity of supporting members 9, and fasteners 10, and other parts desired can be readily taken from stock and assembled as described. The members 9 can be applied to the 40 interior of the building during the erection of the framing or afterwards as desired; and the wall and ceiling board and finishing moldings can thereafter be readily applied when desired.

The construction does not show nails, screws, 45 or other unsightly fasteners on the interior surfaces; and the advantages and utility of such interior finish will be apparent to architects and others familiar with building construction.

We claim:—

1. In a corner finish for wall boards, an angular strip engaging the exterior of adjacent wall boards at the corners of a room, and a molding applied to the interior of the wall boards at the corners thereof opposite said strip, means connecting the molding to the strip to secure the molding in position and clamp the wall boards between the strip and molding, and means for holding the strip in place before the molding is connected to the strip.
2. In a corner finish as set forth in claim 1, said connecting means comprising eye bolts attached to the strip, and hook members attached to the molding engaging said eye bolts.
3. A fastening member comprising a strip having its central portion bent to form a substantially rectangular expandable head, adapted for engagement with a retaining member, and oppositely projecting flanges extending from the sides of the head; and means on the flanges adapted to be forcibly inserted into a wall board when the head is expanded to yieldably grip the wall board between the means and thereby connect the fastening member to the wall board.
4. A fastening member having a portion bent 75

to form a substantially rectangular expandible head adapted for engagement with a retaining member, and oppositely projecting flanges extending from the sides of the head, the outer ends of 5 said flanges being bent downwardly at substantial right angles to the flanges and having prongs adapted to be forcibly inserted into a wall board to yieldably grip the wall board throughout the area embraced by the prongs and thereby connect 10 the fastening member to the wall board.

5. A wall board fastening member, comprising a resilient strip bent to form a substantially rectangular head at its center and having oppositely projecting flanges extending from the sides of the 15 head, the outer ends of said flanges having prongs adapted to be inserted into the wall board with means for expanding the head prior to and during the insertion of the prongs into the wall board, said means being removable after the 20 prongs are inserted.

6. A wall construction for buildings, comprising framing, a plurality of supporting members attached in parallel series to the framing members and having upper and lower converging flanges; 25 boards, and fastening members attached to said boards having heads of greater maximum diameter than the distance between the ends of the flanges of the supporting members, said heads being adapted to be engaged with the said supporting 30 members to secure the boards in position.

7. Interior wall construction for buildings, comprising framing, a plurality of wall supporting members having upper and lower converging flanges attached in parallel series to the interior 35 of the framing, wall boards, and fastening members attached to said wall boards and having angularly bent heads of greater maximum diameter than the distance between the ends of the flanges of the supporting members adapted to be detachably engaged with the said supporting members to secure the wall boards in position.

8. In a corner finish for wall boards; an angular strip engaging the exterior surfaces of adjacent wall boards at the corners of a room; clips 45 engaging the interior surfaces of the boards, means connecting the clips with the strip; a molding applied to the interior of the wall boards opposite the strip; and means independent of the clips for connecting the molding with the strip.

50 9. In a corner finish as set forth in claim 8, said molding connecting means comprising eyes on the strip and wedge members on the molding engaging said eyes.

10. In a corner finish for wall boards, an angular strip engaging the exterior surfaces of adjacent wall boards at the corners of a room, clips 55 engaging the interior surfaces of the boards, members connecting the clips with the strip; and a molding applied to the interior of the wall

boards opposite the strip and readily detachably connected with the said strip.

11. In a corner finish as set forth in claim 10, said readily detachable connection comprising eyes on the strip, and hook members on the 5 molding engaging said eyes.

12. In an interior corner finish for wall boards, an angular strip engaging the exterior surface of adjacent wall boards at the corners of a room, clips pivotally mounted on the strips and engaging 10 the interior surfaces of the boards, a pre-formed molding applied to the interior of the wall boards opposite the strip; and means for readily detachably connecting the molding with the strip. 15

13. In a corner finish as set forth in claim 12, said readily detachable connection comprising eyes on the interior surface of the strip, and wedge hook members on the molding engaging said eyes when the molding is shifted along the boards. 20

14. In an interior corner finish for wall boards, an angular strip engaging the exterior surfaces of adjacent wall boards at the corners of a room, clips pivotally mounted on the strips and engaging 25 the interior surfaces of the boards, the pivots comprising bolts having eyes exposed on the interior of the room; a preformed molding applied to the interior of the wall boards opposite the strip; and hook members on the molding engaging said eyes when the molding is shifted along the boards. 30

15. In an interior wall construction for buildings; framing; a plurality of prefabricated supporting members attached to the framing; prefabricated wall boards carried by the supporting 35 members; and prefabricated moldings carried by the wall boards and covering the joints between wall boards at the angles of the room.

16. In an interior wall construction for buildings; framing; a plurality of prefabricated supporting members attached to the framing; prefabricated wall boards carried by the supporting 40 members; prefabricated moldings carried by the wall boards and covering the joints between wall boards at the angles of the room; and prefabricated corner plates at the junctions of the moldings. 45

17. In an interior wall construction for buildings; framing; a plurality of prefabricated supporting members attached to the framing; prefabricated wall boards carried by the supporting 50 members; prefabricated moldings carried by the wall boards and covering the joints between wall boards at the angles of the room; prefabricated corner plates at the junctions of the moldings; and prefabricated base boards at the lower edges of 55 the walls carried by the supporting members.

DAVID E. ROSS.
